UNITED STATES PATENT OFFICE.

ALFRED C. GILBERT, OF NEW HAVEN, CONNECTICUT, ASSIGNOR TO THE A. C. GILBERT COMPANY, OF NEW HAVEN, CONNECTICUT.

TOY VEHICLE.

Application filed December 16, 1920. Serial No. 431,203.

To all whom it may concern:

Be it known that I, ALFRED C. GILBERT, a citizen of the United States, residing in New Haven, county of New Haven, and State of Connecticut, have invented certain new and useful Improvements in Toy Vehicles, of which the following is a full, clear, and exact description.

This invention relates to toy vehicles and more particularly to those which may be built up or fabricated from standard construction units or elements. These units or elements are so constructed and arranged that they may be assembled to form many different toys. For the sake of economy in manufacture and in order that many different toys may be formed from a small number of construction units, it is necessary that these units be so arranged that the same parts may be associated together in various different relations.

One object of the invention is to provide a new and improved construction toy vehicle, which may be fabricated from a minimum number of different elements.

Another object of the invention is the provision of a set of members which may be associated together in various ways to secure the axles to the body of the vehicle, at different distances therefrom.

Still another object of the invention is the provision of a novel and improved method of attaching the axle securely to the body of the vehicle.

To these and other ends the invention resides in the novel features and combinations of parts to be hereinafter described and claimed.

Fig. 1 is a perspective view of a toy vehicle, of the type known as a glider or coaster, embodying my improvements;

Fig. 2 is a perspective view showing the method of assembly of the rear axle bearing members;

Fig. 3 is a perspective view showing the method of assembly of the front axle bearing members; and

Fig. 4 is a perspective view of a modified method of assembling the members to construct the rear axle bearing.

The toy vehicle to which I have shown my improvements applied consists of an elongated frame or body portion, which is made up of two relatively long frame members 11. These frame members are of angle

cross-section and are in turn formed of the metal strips 12, two of which are spliced together in abutting relation in the formation of one of the frame members 11. The strips 12 are perforated, as shown, so that two abutting members may be placed end to end and a metal strap 13 applied and bolted thereto, so that the two strips will form one long rigid member. The angle members are then formed by joining two of the long rigid members thus formed by means of the perforated brackets 14, which may be secured to these strips by means of the perforations therein to connect them in as many places as will be found desirable to form a rigid member. These two frame members 11 may then be joined in spaced relation by a plurality of strap members 15, which are placed at desirable and convenient points along the length of the same, to form the body member of the vehicle. To the front end of the body is connected a V-shaped bracket 16, which is so shaped at the ends thereof that it may be bolted to both strips 12 of the frame members 11, so that these brackets assist in holding these strips in assembled relation. To the lower portion of this bracket is connected a clip 17 by means of a bolt 10, which clip is perforated to receive the front axle 18 carrying the two wheels 19. A pin 20 may be inserted through perforations in the axle on each side of each of the wheels 19 to prevent the movement of the wheels longitudinally of the axle. To prevent longitudinal movement of the axle within the clip 17 a second clip 21 is adapted to embrace the axle and to fit between the legs of the clip 17 and it is provided with a set screw 22, which when tightened, will secure the axle in position. It is seen that the parts thus far described may be assembled, as set forth to provide a rigid body member which has an axle pivotally connected thereto and securely held in position. This pivotal connection is provided about the bolt which joins the bracket 16 to the clip 17.

It is common in toy vehicles of the glider and coaster type to provide rear wheels that are of greater diameter than the front wheels. This difference in the size of the wheels appears in the embodiment of my invention shown in the drawings and it is particularly apt to be true in toys of the type shown where the parts are used in

the construction of other toys. The rear axle 23, which carries the larger wheels 24, is of course supported at a greater distance from the ground than the front axle 18. If, then, the axle bearing construction, shown in Fig. 3, for use with the front axle, is used in connection with the rear axle, the body of the vehicle would not be supported in a level position but would be inclined forwardly. It is, therefore, impracticable to use the assembly shown in Fig. 3 for the rear axle bearing, but in the interest of economy it is expedient to use, if possible, some or all of the same members, assembled in a different relation, rather than to manufacture other members of smaller size, which, it is apparent, would increase the cost of the toy set.

I have therefore devised the constructions shown in Figs. 2 and 4, which use the same construction units as the bearing assembly shown in Fig. 3, but mount the body supporting V-bracket below the axle instead of above, thereby making just enough difference in the height of the bracket to compensate for the difference in diameter of the wheels.

To assemble the parts as shown in Fig. 2, one of the V-shaped brackets 16', identical in shape and size with the V-shaped bracket 16, is secured within the U-shaped clip 17', by the bolt 10'. The bracket, in this position, is, of course, non-rotatably held within the clip 17'. A second U-shaped clip 21' is then placed with one of its legs between those of the clip 17' and the axle 23 is inserted through the aligned openings in the clips. When in proper position the set screw 22' is tightened and the parts will then be held against longitudinal displacement upon the axle. In this arrangement the bracket 16' is mounted non-rotatably upon the axle while, as shown in Fig. 3, the front axle 18 and clip 17 may rotate about the bolt 10 to steer the vehicle.

A slightly different arrangement is shown in Fig. 4, wherein the clip 21' is placed entirely within the clip 17', instead of being placed in a straddling position as shown in Fig. 2. Otherwise the parts are assembled as in Fig. 2 and the body supporting bracket 16' is held in the same position as in that figure.

A body or seat member 25 may be secured to the frame members 11 by bolts 26 passing through perforations 27 in the member 25.

As shown, the seat member contains a number of perforations so that it may be secured upon the body in various relations.

In practice the parts of the toy are, when

detached, packed in a box and the seat member 25 forms a lid for the packing box. Spacing brackets (not shown) are usually mounted on the frame members 11 below the seat 25.

It is apparent that I have provided a strong and substantial construction toy, which may be economically manufactured and which excels in appearance, strength and durability, many of the permanently built toys now upon the market.

As shown, the parts of my toy vehicle are all constructed of metal but the particular material used may, of course, be varied without departing from my invention.

While I have shown and described one embodiment of my invention, it is to be understood that I do not limit myself thereto in all of its details as various changes may be made without departing from the spirit of the invention or from the scope of the appended claims.

What I claim is:

1. In a toy vehicle, a body, front and rear axles, similar brackets to support said body from said axles, one of said brackets being supported at a point above one axle, and another of said brackets being supported at a point below the other axle to support the body at different distances from said axles, and a set of securing members fastened to the axle to secure said brackets against longitudinal movement thereon.

2. In a toy vehicle, a body, an axle, a substantially V-shaped bracket secured to said body, a U-shaped clip embracing said axle, said axle lying within the apex of the bracket, said bracket being connected to said clip at a point below said axle.

3. In a toy vehicle, a body, an axle, a substantially V-shaped bracket secured to said body, and a U-shaped clip having its legs embracing said axle and the base depending therefrom, the apex of said bracket being secured to the upper face of said clip base at a point below said axle, so that said body is suspended from the axle.

4. In a toy vehicle, a body, an axle, a substantially V-shaped bracket secured to said body, a U-shaped clip embracing said axle, said bracket being connected to said clip at a point below said axle, and a second clip secured to the axle and straddling one of the legs of said first clip to prevent longitudinal movement of said axle relative to said first clip.

In witness whereof, I have hereunto set my hand on the 8th day of December, 1920.

ALFRED C. GILBERT.
